UNITED STATES PATENT OFFICE.

CHAUNCEY BUCKLEY, OF MERIDEN, CONNECTICUT, ASSIGNOR TO THE CHARLES PARKER COMPANY, OF SAME PLACE.

CARTRIDGE-CLOSING MACHINE.

SPECIFICATION forming part of Letters Patent No. 239,930, dated April 12, 1881.

Application filed December 22, 1880. (No model.)

To all whom it may concern:

Be it known that I, CHAUNCEY BUCKLEY, a citizen of the United States, residing at Meriden, in the county of New Haven and State of Connecticut, have invented certain new and useful Improvements in Cartridge-Closers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to cartridge-closers; and it consists in the construction and combination of parts, hereinafter set forth.

In the accompanying drawings, Figure 1 represents a perspective view of my improved cartridge-closer, the sliding closing-cup being in position to engage with the cartridge-case. Fig. 2 represents a perspective of the same, showing the cartridge-closing cup withdrawn from such engagement. Fig. 3 represents a detail 25 perspective view of the sliding shaft, shifting-lever, and crank-arm. Fig. 4 represents a detail view of the cartridge-closing cup, showing the interior thereof; and Fig. 5 represents a detail view of the fixed socket or cartridge-holder.

30 A designates the stock or frame of the implement, which consists, mainly, of a forward arm, a , a rearward arm, a' , and an arm, a'' , through which a clamp-screw, A' , works upward to hold the said stock on the bench in the usual manner. On the forward arm, a , are erected two tubular bearings, b b , which are connected by an arc-shaped metallic bar, B. On the outer end of the rearward arm, a' , is a raised block or standard, b' . The foregoing parts, except clamp-screw A' , are preferably cast in one piece.

C designates a triangular cartridge-holder or socket, which is rigidly secured to the inner face of block or standard b' , and provided 45 with prongs which extend horizontally in the direction of the bearings b b . The closed end of the cartridge is received in the space between these prongs, which are parallel to the sides of the said closed rear end. They fit it

tightly, and thereby hold the cartridge motionless. The spaces between the prongs allow the ready insertion of the operator's thumb and finger to remove the cartridge from said holder after the closing is finished. To make this operation still easier the sides of the triangle are cut away in curved lines. This special construction of the cartridge holder or socket is not, however, essential to the most important part of my invention, as any other holder or socket might be used which would keep the cartridge motionless.

D designates the closing-cup, which has on its inner face a hub, d , surrounded by a groove, d' , within which are knobs or teeth d'' . The edge of the open end of the cartridge-case is received in this groove, and engaged by said teeth or knobs when said closing-cup is rotated. This effects the closing of the cartridge in the usual manner. Said closing-cup is attached to and moves with the end of a shaft, E, which has both rotary and longitudinal motion in bearings b b , already described. The rotary motion of said shaft is communicated through crank-arm F, which is keyed on the other end of said shaft. The longitudinal motion of the latter is communicated through a lever, G, of the first kind, which is pivoted to bar B and vibrates in a vertical plane. The lower end of said lever is forked, and the rounded ends of the two tines g g of 80 said fork set into a deep groove, e, formed around and in the middle part of shaft E. The upper end of said lever is provided with a handle, G'.

The operation of my cartridge-closer is as follows: The stock A is first firmly clamped on a bench or other stationary thing or structure. The closed end of the cartridge is then introduced into the holder C. The handle G' of lever G is then rocked toward crank F, thereby causing said lever to move shaft E and closing-cup D in the opposite direction. This motion brings the closing-cup against the open end of the cartridge. The crank-arm F is then operated to rotate said shaft and closing-cup, thereby closing said open end, as stated. The motion of lever G is then reversed to withdraw said cartridge-closing cup from the cartridge, and

the latter is removed from holder C. Another cartridge may then be put in its place and the operation repeated.

The shaft E and the bearings through which it passes may be screw-threaded.

Having thus described my invention, what I claim as new, and desire to secure by Letters Patent, is—

1. The combination of frame A, having arm 10 a^2 , and arc-shaped bar B, with screw A' for clamping said frame to a bench, fixed cartridge-holder C, closing-cup D, horizontal shaft E, lever G, pivoted to bar B, and engaging shaft E, to move the same longitudinally, and crank-arm F, secured on shaft E, all constructed and 15 operating substantially as set forth.

2. Stock A, having tubular bearings b b , and arc-shaped bar B, connecting said bearings, in combination with shaft E, grooved at 20 e and sliding through said bearings, crank-arm F, and lever G, pivoted to bar B, and provided with tines g , which set into said groove and operate said shaft, substantially as set forth.

In testimony whereof I affix my signature in 25 presence of two witnesses.

CHAUNCEY BUCKLEY.
